PREMIUM STAMP-DISPENSING MECHANISM
FOR CASH REGISTERS
Robert C. Clark, Lansing, Mich.
(192 Lexington Ave., Needham, Mass.)
Filed June 25, 1958, Ser. No. 744,409
1 Claim. (Cl. 235—7)

This invention relates to a mechanism for dispensing premium stamps and particularly to such a mechanism which operates in conjunction with a cash register.

In recent years it has become common practice for retailers and tradesmen to give premium stamps to the customer in proportion to the amount of the sale, the stamps being redeemable for merchandise. The stamps are commonly dispensed by the clerk or cashier by tearing the proper amount off a sheet containing a large number of stamps. Such a procedure requires a great deal of time and thought on the part of the clerk or cashier, resulting in a reduced efficiency.

It has heretofore been suggested that a separate stamp-dispensing machine be provided which is actuated separately by the cashier or clerk to dispense the required number of stamps. Such machines have two important disadvantages. First, they require mental thought on the part of the clerk or cashier in order to establish the number of stamps to be dispensed. In addition, they require a separate manual manipulation of the mechanism which may be on the order of a cash register. Thus, even a stamp-dispensing mechanism of this type involves a separate operation on the part of the cashier.

It is therefore an object of this invention to provide a mechanism which will automatically provide the required number of stamps when the total of purchases is registered on the cash register or other tabulating machine which is used to total the purchases.

It is a further object of this invention to provide such an apparatus which can be easily attached to cash registers without any substantial change thereto.

In the drawings:

FIG. 1 is a fragmentary front elevational view of a cash register having mechanism embodying the invention attached thereto.

FIG. 2 is a fragmentary sectional view taken along the line 2—2 in FIG. 1.

FIG. 3 is an end elevational view of the mechanism shown in FIG. 1 with the end cover open, the cash register being shown in dotted lines.

FIG. 4 is a fragmentary sectional view taken along the line 4—4 in FIG. 1, the cash register being shown in dotted lines.

FIG. 5 is a fragmentary sectional view taken along the line 5—5 in FIG. 1.

FIG. 6 is a fragmentary sectional view on an enlarged scale taken along the line 6—6 in FIG. 5.

FIG. 7 is a perspective view on an enlarged scale of a portion of the mechanism shown in FIG. 6.

FIG. 8 is a fragmentary sectional view on an enlarged scale taken along the line 8—8 in FIG. 1.

FIG. 9 is a fragmentary sectional view on an enlarged scale taken along the line 9—9 in FIG. 4.

FIG. 10 is a fragmentary sectional view taken along the line 10—10 in FIG. 9.

FIG. 11 is a fragmentary sectional view taken along the line 11—11 in FIG. 8.

FIG. 12 is a perspective view of the stamp-dispensing mechanism removed from the cash register.

FIG. 13 is a fragmentary sectional view on an enlarged scale taken along the line 13—13 in FIG. 3.

FIG. 14 is a fragmentary plan view of a strip of stamps as used in the stamp-dispensing mechanism.

Referring to FIGS. 1 and 12, the stamp-dispensing

2

mechanism 20 is attached to a cash register 21 which is of the type which totals the purchases and registers the total so that it is visible to the customer in an indicator box 22 on the register. Stamp-dispensing mechanism 20 is operable incident to the indication of the total in the box 22 to dispense the required number of stamps.

Referring to FIG. 12, the stamp-dispensing mechanism 20 comprises a housing having a first section 20a disposed at the side of the cash register and a second section 20b disposed to the rear of the cash register. As shown in FIG. 3, three rolls 23a, 23b, 23c of premium stamps are rotatably mounted in the housing section 20a of the stamp-dispensing mechanism. The rolls 23 are of predetermined width. By way of example the roll 23a has a width of one stamp and the rolls 23b, 23c are five stamps wide.

As shown in FIG. 13, each roll of stamps is rotatably mounted between intermediate wall 24 and end wall 25 of the section 20a by a structure which includes a fixed spindle 26 and a movable spindle 27 mounted on an arm 28 which is pivoted to end wall 25.

As shown in FIG. 13, stamp roll 23 is rotatably held on the spindles 26, 27. Cover 29 is hinged to the rear edge of the housing 21 so that it can be swung open as shown in FIG. 3 to provide access to the rolls 23. To remove and replace the roll, lever 28 is swung outwardly and upwardly with cover 29 open. Cover 29 is held in closed position by a rotatable latch 30 which engages a tab 31 on the housing (FIG. 3).

When the total of purchases is registered on cash register 21, a predetermined length of stamps is fed from each of the rolls 23, as required by a mechanism which includes a drive roll 32 fixed on a shaft 33 which is rotatably mounted between fixed end wall 25 and intermediate wall 24 of housing 21 (FIG. 11). Drive rolls 32 are provided with circumferentially spaced teeth 34 which engage the conventional perforations 35 between successive stamps S in a strip (FIG. 14) so that when each drive roll 32 is rotated a strip of stamps is fed from each supply roll.

A friction roll 36 is provided adjacent the periphery of each drive roll 32. The strip of stamps from the supply roll is passed and threaded between the friction roll 36 and drive roll 32. A horizontal guide plate 37 is provided to guide the strips of stamps outwardly of housing 20 through dispensing openings 38a, 38b and 38c, respectively (FIGS. 1, 8 and 12). In addition, a knife 39 is provided to sever each previously fed strip of stamps and permit them to fall into an open tray 40 (FIGS. 8 and 12). As shown in FIG. 11, a hand crank 33a may be inserted in the end of shaft 33 in order to provide an easy means for rotating shaft 33 and feed roll 32 in threading a strip of stamps or in clearing the end of a strip of stamps.

Rectangular chutes 41 are provided to guide the severed strips in their movement downwardly through openings 38 toward the tray (FIG. 8). In addition, guide blocks 42 are provided above the plates 37 to insure that the strips of stamps will move in a flat plane into proper alignment with the knives.

Referring to FIG. 1, the intermittent rotation of drive rolls 32 is obtained through one-way clutches 43. For example, as shown in FIG. 11, one-way clutch 43 on shaft 33 provides an intermittent drive to drive roll 32.

Clutches 43 are, in turn, driven by linkages to the cash register as presently described. Each clutch 43 is driven an amount such that the required number of stamps are fed from the rolls 23 when purchases are tabulated on the cash register. The arrangement is such that a number of stamps is fed from each roll corresponding to the numerical value of each digit in the amount tabulated by the register. For example, if a stamp is to be dispensed for

each ten cents of purchases, a strip of stamps, one stamp in width, is fed from roll 23a of such a length that the number of stamps corresponds in number to the digit in the tenths of dollars in the amount tabulated by the register; a strip of stamps, five stamps wide, is fed from roll 23b of such a length that the number of stamps is ten times the numerical value of the digit in dollars in the amount tabulated; and a strip of stamps, five stamps wide, is fed from roll 23c of such a length that the number of stamps is one hundred times the numerical value of the digit in tens of dollars in the amount tabulated. Thus, for example, if the amount tabulated by the cash register were \$14.53, the clutches 43 would be driven so that five stamps would be fed from roll 23a; forty stamps would be fed from roll 23b, that is, a strip five stamps wide and eight stamps long; and one hundred stamps would be fed from roll 23c, that is, a strip five stamps wide and twenty stamps long.

In one conventional type of cash register 21 there are provided a plurality of groups of indicator plates, each group of plates bearing numbers from 0 to 9; the indicator plates in one group corresponding to cents unit digits, the indicator plates in another group corresponding to cents in tens digits, the indicator plates in another group corresponding to dollars in unit digits, and the indicator plates in still another group corresponding to dollars in tens digits. When the total of sales is tabulated and computed by the cash register, the proper indicator plates are elevated from each group by the register mechanism into indicator box 22 to indicate the total.

Referring to FIG. 2, there is illustrated one conventional cash register mechanism constructed such that when the total of purchases is computed by the cash register, indicator positioning bars 44 in the cash register are shifted axially, that is fore and aft of the cash register, by a conventional mechanism not forming a part of this invention, to move each group of indicator plates an amount corresponding to the numerical value of the digit with which each group is associated in the amount computed and thereby bring predetermined indicator plates into position so that they can be raised into indicator box 22 by an indicator operating bar 45 which is moved upwardly (FIG. 6). The movement of each bar 44 is therefore proportional to the number that is to be shown in indicator box 22. For example, if in a particular digit the number is to be zero there will be no movement of the corresponding bar 44, whereas if the number is to be a 9 there will be substantial movement of the bar 44.

The movement of bars 44 is transmitted to the drive rolls 32 so that the drive rolls are rotated in proportion to the movement of their respective bars to feed the required number of premium stamps.

The drive means for drive rolls 32 are shown in FIGS. 2 and 5, and include concentric tubular shafts 46a, 46b rotatably mounted on a shaft 46c journaled between spaced walls 24 and 47 and extending through wall 48 at the rear of the stamp-dispensing mechanism and substantially within the housing 20b. Gears 49 are fixed to the shafts 46. Gear racks 50 are pivoted to the rear ends of the indicator positioning bars 44 and extend through openings in the front walls of housing 20b (FIG. 12). Racks 50 may be moved downwardly into mesh with gears 49 or upwardly out of mesh with gears 49.

Referring to FIGS. 2 and 4, sprockets 51 are fixed to the ends of the shafts 46. Drive chains 52 are trained over the sprockets 51 and gears 53 of the clutches 43. Idler sprockets 54 are provided on some of chains 52.

Racks 50 are normally maintained out of mesh with their respective gears 49 by a mechanism which comprises levers 55 fixed on a shaft 56 pivoted in housing 20b (FIG. 2). Shaft 56 has fixed thereto a short arm 57 (FIG. 5) connected by a rigid link 58 to an actuating lever 59 pivoted on wall 24 as at 60. Lever 59 has a manually operable handle 61 projecting through an opening 62 in housing 20a. Stops 63, 64 are provided on wall 24

to limit the movement of lever 59. The free ends of levers 55 are provided with rollers 65 which ride in slots 66 in the respective racks 50 as shown in FIG. 5.

When it is desired to transmit the movement of the indicator positioning bars 44 to drive rolls 32 and feed the stamps, lever 59 is moved downwardly from the dotted line position shown in FIG. 5 to the position shown in full lines. This causes the racks 50 to mesh with gears 49. Thus, when the indicator positioning bars 44 are moved axially they will rotate gears 49 and, in turn, their respective shafts 46 and drive clutches 43 through the sprockets 51, gears 53 and chains 52 and rotate the drive rolls 32 to feed the stamps. Any movement of the indicator positioning bars 44 in the opposite direction does not affect the drive rolls since clutches 43 are of the one-way type.

Mechanism is provided for returning lever 59 to its original position (shown in dotted lines in FIG. 5) after each totaling operation thereby moving racks 50 out of engagement with gears 49. This mechanism includes a spring-loaded latch 67 pivoted to the wall 48 of the stamp mechanism and adapted to engage a projection 68 on lever 59 when lever 59 is rotated to bring the racks 50 into engagement with the gears 49 (FIG. 6). Lever 59 is normally urged in a clockwise direction as viewed in FIG. 5 by a cable 69 trained over pulleys 70 and connected at one end to lever 59 and its other end to a tension spring 71 fixed to the housing of the mechanism. When lever 59 is rotated in a counterclockwise direction as viewed in FIG. 5, projection 68 on lever 59 is brought into engagement with latch 67 and locks lever 59 in the position shown in full lines wherein racks 50 are in mesh with gears 49.

Indicator operating bar 45 within cash register 21 (FIGS. 5 and 6) moves upwardly when the register is operated to present the indicator plates into view in indicator box 22. A small lever 72 is pivotally mounted on bar 45 and projects outwardly through the side wall of the cash register so that when the bar 45 moves upwardly the end of small lever 72 engages a tab 73 on latch 67 to pivot the latch in a clockwise direction thereby releasing projection 68 and permitting lever 59 to move in a clockwise direction under the action of cable 69 and spring 71 thereby moving racks 50 upwardly out of engagement with gears 49. The inner end of small lever 72 abuts a portion of indicator operating bar 45 so that it is limited in permissible clockwise movement (FIG. 6) but may be pivoted counterclockwise without engaging tab 73 when the operating bar is moved downwardly.

In order to prevent rotation shafts 46 while out of engagement with racks 50, a plurality of pawls 74 are fixed to a rockable shaft 75 which, in turn, is connected to arm 57 by a crank 76 and link 77 (FIG. 5). When racks 50 are moved out of engagement with their respective gears 49, pawls 74 are moved into engagement with gears 49 to prevent rotation of the gears.

As shown in FIG. 9, knives 39 are pivoted adjacent one end to wall 48 for vertical movement and are connected at their opposite ends to cable 69. When the knives are pivoted downwardly by cable 69, their cutting edges cooperate with the forward edges of plates 37 to sever the strips of stamps advanced by drive rolls 32.

The operation of the stamp-dispensing mechanism and register may be summarized as follows:

In tabulating purchases the cashier operates the cash register 21 in the normal fashion by depressing the proper keys 80 for each purchase and registering each purchase by depressing bar 81. After all of the purchases have been tabulated a sub-total is taken by depressing the sub-total key 80a on the register and again depressing bar 81. To deliver the required number of stamps when the sub-total is taken, the cashier grasps the handle 61 and moves it downwardly before depressing bar 81.

Movement of the handle 61 downwardly causes the link 58 to pivot crank 57 and move racks 50 into mesh with gears 49 through the levers 55. When the operator thereafter depresses bar 81 the cash register operates to indicate the sub-total of purchases in indicator box 22. During this operation of the cash register, indicator operating bar 45 is moved downwardly and the indicator positioning bars 44 are moved axially to bring the indicator plates to a zero or neutral position. During the downward movement of the indicator operating bar actuation of tab 73 is prevented because of the counter-clockwise pivoting of the lever 72 (FIG. 6). During the axial movement of the indicator positioning bars there is no movement transmitted to feed stamps because of the one-way action of clutches 43. As the cash register continues to operate, indicator positioning bars 44 are moved axially a predetermined amount to bring the proper indicator plates into position so that they can be elevated into the indicator box. This proportional movement of indicator positioning bars 44 is transmitted through shafts 46, sprockets 51, chains 52 and gears 53 to clutches 43 which drive rolls 32 and thereby feed a predetermined number of stamps from each of the stamp rolls 23. It will, of course, be understood that the size of the gears, sprockets and feed rolls is such that for a predetermined movement of the indicator positioning bars 44, the proper length of strip of stamps is fed from the stamp rolls 23.

During the operation of the cash register after the indicator positioning bars 44 have been moved axially a predetermined amount, indicator operating bar 45 is moved upwardly to position the proper indicator plates in the indicator box 22. This final movement of the indicator operating bar 45 upwardly causes small lever 72 on operating bar 45 to strike latch 67 and disengage lever 59, permitting spring 71 to move cable 69 and return lever 59 to its original position. During this movement cable 69 also pivots knives 39 downwardly cutting off the strips of stamps which have been fed. The severed strips fall into tray 40 so that the cashier can pick them up and give them to the customer without any further operation on his part.

When lever 59 is returned to its original position, racks 50 are pivoted upwardly out of contact with gears 49 and pawls 74 are moved into engagement with gears 49 through links 77 and cranks 76 to lock gears 49 against further rotation.

The cash register is now in condition for a further operation such as the tabulation and computation of purchases for which stamps are not given or the addition of sales tax and the like to the sub-total.

Instead of utilizing rolls of stamps containing a single layer or strip, the roll may comprise a multiple layer or

strip, thus reducing the length of strip that must be fed from each roll.

In addition, instead of using rolls, a continuous strip of stamps folded back and forth in a suitable container 5 may be provided in place of each supply roll.

It can thus be seen that I have provided a stamp-dispensing mechanism which is operable in conjunction with a cash register so that at a desired time the required number of stamps are not only fed but also severed and 10 provided to the customer. At the end of each feeding operation the mechanism is disengaged automatically from the drive of the cash register so that the cash register may be operated in normal fashion without any further thought on the part of the operator as to whether or not 15 the stamp-dispensing mechanism is present.

I claim:

In a cash register of the type wherein the total of purchases is tabulated and brought to the view of an observer by movement of a plurality of indicator plates 20 bearing digits vertically upward into an indicator area, said indicator plates being selected from a plurality of indicator plates by predetermined movement of the indicator positioning members in a generally horizontal direction, the combination comprising a housing mounted 25 on said register, means for rotatably mounting a plurality of stamp rolls in said housing, a feed mechanism for each said roll for feeding a strip of stamps from said roll, drive means for each said feed mechanism responsive to the movement of said indicator positioning members 30 for driving said feed mechanism of said roll to feed a strip of stamps proportional in length to the digit on the corresponding indicator plate, each said latter means including a rack pivoted to a respective indicator positioning member, a gear, means for moving said rack into and out of engagement with said gear, means interconnecting said gear to said feed mechanism, and single manually 35 operated means for actuating said rack engaging and disengaging means to move said racks into and out of engagement with their respective gears, said single manually operated means comprising a shaft, a lever for each rack fixed to said shaft, a slot in each said rack, the end of each said lever being slidably mounted in the slot in its respective rack, a handle pivoted in said housing, and means forming an operative connection between said handle and said shaft for rotating said shaft and pivoting said levers to move said racks into and out of engagement with their respective gears.
